UNITED STATES PATENT OFFICE.

EMANUEL CINER, OF NEW YORK, N. Y.

DESIGN FOR A RING OR SIMILAR ARTICLE.

SPECIFICATION forming part of Design No. 37,200, dated November 1, 1904.

Application filed September 10, 1904. Serial No. 224,042. Term of patent 3½ years.

To all whom it may concern:

Be it known that I, EMANUEL CINER, a citizen of the United States, residing in the city of New York, borough of Manhattan, county and State of New York, have invented a new, original, and ornamental Design for a Ring or Similar Article, of which the following is a specification.

My new design is illustrated in the accompanying drawings, forming part hereof, wherein—

Figure 1 is a perspective view of a ring embodying my design. Fig. 2 is a plan view thereof. Fig. 3 is a side elevation thereof.

What I claim is—

The ornamental design for a ring or similar article, as herein shown.

EMANUEL CINER.
